MINE CAR

Armistead R. Long, Scarbro, W. Va.

Application November 16, 1928
Serial No. 319,390

11 Claims. (Cl. 213—220)

This invention relates to improvements in mine cars.

The primary object of this invention is the provision of an improved end sill and bumper construction for mine cars, which is very strong, and in which the coupling parts are readily accessible, without danger to an operator.

Other objects and advantages of this invention will be apparent during the course of the following detailed description.

In the accompanying drawings, forming a part of this specification, and wherein similar reference characters designate corresponding parts throughout the several views,

Figure 1 is a longitudinal sectional view taken through an end of the mine car, showing more particularly the structural assemblage of the parts of the end of the car.

Figure 2 is a fragmentary plan view of an end of the improved mine car.

Figure 3 is a fragmentary end view of the end sill structure of the mine car.

Figure 4 is a perspective view showing the preferred end structure of the bottom plate of the mine car.

Figure 5 is a perspective view of an angle draw bar.

Figure 6 is a perspective view of an upper angular shaped end sill member.

Figure 7 is a perspective view of a wood filler block.

Figure 8 is a perspective view of a reinforcing angular shaped end sill member.

Figure 9 is a perspective view of the end sill supporting member.

Figure 10 is a perspective view of the channel shaped bumper member.

Figure 11 is a longitudinal sectional view taken through a modified form of end sill for a mine car.

Figures 12, 13 and 14 are respectively perspective views of details of the form of invention shown in Figure 11.

In the drawings, wherein for the purpose of illustration are shown preferred and modified forms of the invention, the letter A generally designates the preferred form of mine car, which may include conventional side chassis beams or sills B and C, to which a floor D may be secured in any approved relation, and at the ends of which end sill or bumper structures E may be secured, at both ends of the mine car, in accordance with usual construction.

The side sills are of usual channel-shaped formation, with the channel grooves facing out-

ward, and the bottom D may be of usual mine car construction, and secured to said side sills in any approved relation. The floor as well as the side sills are of metal, and the floor D for the preferred form of invention is provided with rearwardly projecting horizontal flanges 20 and 21, shown in Figure 4, with a space 22 therebetween thru which the angular shaped draw bar member 23, shown in Figure 5 of the drawings, may extend, in accordance with the structural assemblage to be further described. The flanges 21 and 20 are provided with openings 24 along their marginal portions, to receive rivets 25 for securing the floor at its end to the frame end sill supporting member 26.

The supporting member 26 is of metal, sufficiently strong for the purpose, and comprises a rectangular plane wall or body 27, comprising attaching flanges 28 and 29 bent normal thereto at the ends thereof; said flanges 28 and 29 being provided with rivet receiving openings 30, and the said flanges 28 and 29 being intended to lie within the channel grooves at the ends of the side sills, as shown in Figure 2 of the drawings, in contact against the webs of the channel side sills B and C, for securement thereto, as by rivets 33. Thus the upright wall 27 lies across the end of the mine car, at right angles to the axis thereof, and for the preferred form of invention the said plate 27 is provided with a stiffening and attaching flange 35 along the upper margin thereof, extending the length of the plate 27, and which in depth is relatively short, so as not to interfere with coupling details to be subsequently described. The flange 35 is provided with a plurality of openings 36 along the margin thereof, which are adapted to align with the openings 24 of the extensions 20 and 21 of the metal floor overlying the top of the flange 35, for receiving rivets 25 above mentioned, and as shown in Figures 1 and 2 of the drawings.

An L-shaped angular metal reinforcing member 40 is provided, which includes the upright wall 41 shown in detail in Figure 8 of the drawings, which is substantially the same length as the back wall 27 of the member 26, and which lies at the outer side against the wall 27 in a reinforcing relation therewith and is riveted thereto in a manner to be subsequently described. The top edge 42 of the wall 41 fits against the under surface of the flange 35, and at its lower margin the wall 41 is provided with the horizontal flange 43, which may be referred to as the lower flange, and which is bent normal to the wall or plate 41. The corners of the

flange 43 are removed, so that the flange 43 in accordance with usual construction tapers from the sides thereof convergently towards the free edge 44 thereof, which is preferably arcuated convexly. The upright wall 41 is not quite as high as the wall 27 of the member 26, so that the supporting flange 43 is disposed in a plane slightly above the lower marginal portion of the wall 27, as is shown in Figure 1.

10 A second metal angle member 46 is provided, which has an upright wall or web 47 of the same length or substantially the same length as the walls 27 and 41 of the members 26 and 40 respectively, and which is adapted to lie at the outer 15 surface of the wall 41, immediately beneath the flange 35 of the supporting member 26, as shown in Figure 1 of the drawings. The height of the wall 47 is considerably less than the height of the wall 41. The angle member 46 includes 20 also a horizontal supporting and attaching flange 48, which may be referred to as the upper flange, since it is spaced above the flange 43 of the member 40. In assemblage the edge 50 of the angle member 46 is disposed flush with the 25 top edge 42 of the wall or web 41 of the member 40, as shown in Figure 1 of the drawings, with the reinforcing uprights or plates 41 and 47 in abutment with each other, and in relation to the wall 27 above described, and as shown in 30 Figure 1 of the drawings. At opposite sides of the medial portion of the wall 27 and the reinforcing uprights 41 and 47, there are provided on the walls or uprights 27, 41 and 47 respectively a series of openings 52, 53 and 54, which 35 align to receive rivets 56, by means of which to rivet the plate or wall parts 27, 41 and 47 in abutting relatively reinforcing relation, as shown in the drawings. This spaces the horizontal lower and upper flanges 43 and 48 in spaced 40 parallel relation, and said flanges are similarly formed at their marginal portions, so that the peripheral end edges thereof lie in the same vertical planes. Between said horizontal flanges is provided a space within which a wood filler piece 45 59 is disposed.

The angle clip-like draw bar 23 includes the attaching flange or leg 60, having openings 61 therethrough, adapted to align with openings 63, 64 and 65 in the walls or upright plates 27, 50 41 and 47 respectively, for receiving rivets 66, as shown in the drawings. The draw bar clip 23 also includes the horizontal draw bar body 55 or flange 68 which extends horizontally forward above and in contact with the attaching flange 35 of the end sill member 26, and which draw bar body is provided with openings 70 60 therein adapted to align with opening 71 in the outer marginal portion of the flange 35, and thru which openings rivets 25 are extended to 65 secure the draw bar body 68 in a reinforced braced relation as close to the outer end of the draw bar body as convenient. The outer portion of the draw bar flange or body 68 is provided with a coupling pin inserting opening 72, through which the coupling pin 73 is adapted to 70 be detachably inserted, so that the head 74 of said coupling pin rests on top of the draw bar body 68, in accordance with usual construction. The recess 22 is cut in the mine car floor D in order to accommodate the draw bar body 68 in the relation of structure above described, and as is shown in Figures 1 and 2 of the drawings.

The upper and lower flanges 48 and 43 respectively, receive the flat filler block 59 therebetween in substantially a conforming relation. The rear

surface 75 of the filler block 59 abuts against the front surface of the lower portion of the reinforcing wall 41, as shown in Figure 1, and in this position the outer marginal portions of the filler block project beyond the outer edges of the said flanges 43 and 48, as shown in Figures 1 and 2 of the drawings, so that the abutting forces will be taken up in the filler block 59, which is preferably of wood, although it may be of other material, and more yieldable than the other metal parts of the composite bumper or end sill structure. The flanges 43 and 48 are respectively provided with openings 78 and 79, in their outer ends, along the medial line thereof, through which the coupling pin 73 extends, as shown in Figure 1 of the drawings. The filler block 59 is provided with an opening 80 therethrough, which is elongated along the axis of the mine car, and thru which the coupling pin shank also extends. The filler piece 59 engages at its upper and lower surfaces in sliding contact with the faces of the flanges 43 and 48.

A channel-shaped metal bumper piece 82, best shown in detail in Figure 10, is provided, including upper and lower horizontal flanges 83 and 84, and a bight portion 85 which is concavo-convexly arcuated in the plane of the flanges 83 and 84. The channel piece is straddled above and below the flanges 43 and 48, in the relation shown in Figure 1, with the inside surface of the arcuated bight or connecting portion 85 abutting against the forward projecting part of the filler block 59, as shown in Figures 1 and 2 of the drawings. The flanges 83 and 84 are provided with elongated openings 87 therein, adjacent the free ends of the flanges, through which bolts 88 are disposed; the bolts 88 being detachably connected through suitable openings 89 and 90 in the flanges 43 and 48 respectively, and two elongated openings 91 in the filler block 59, as is shown in the details of these parts in Figures 6, 7, and 8 of the drawings. The flanges 83 and 84 of the channel-shaped metal bumper 82 are each provided with elongated openings 93, adapted to align with the openings 78, 79 and 80 above described, to receive the shank of the detachable coupling pin, in the relation shown in Figure 1 of the drawings.

It is quite apparent that shock occasioned by the bumping of the end sill structure, at the bumper member 82 will be transmitted to the bumper member 82 will be transmitted to the rather yieldable filler block 59, without placing a strain or shearing effect upon the coupling pin 73; it being understood that the bumper channel 82 may move relative to the upper and lower flanges 48 and 43 to accomplish this result.

The coupling chain 95 is of course detachably connected at one of its links to the shank of the coupling pin in the space below the draw bar body 68, and the chain 95 when inoperative may be supported in a protected relation inwardly out of obstructing relation with the bumping parts of the end sill, as shown in Figure 2, by providing a substantially U-shaped retaining bolt 97, slidably supported at the body portion 98 thereof in a series of aligned openings 99 provided through the three thicknesses of the plates 27, 41 and 47; the bolt 97, at the inner side of the end sill below the mine car bottom having a retaining extension 100 transverse thereto, and forwardly of the reinforcing wall 47 being provided with a normally downturned latch extension 101 provided with an enlargement 102 on the lower end thereof. By gravity the bolt 97 assumes an inverted U-shaped position, with the head 102 of the extension 101 spaced above the horizontal upper flange 48 for

a distance less than the thickness of the end link of the chain 95, so that, as shown in Figures 2 and 3 of the drawings, the chain when inoperative may be linked over this extension 101 and retained in an out of the way position upon the end sill. Of course, to detach the chain from the U-shaped retaining bolt 97, it is merely necessary to turn the same sidewise and release the end link therefrom in a manner which is obvious.

10 In the provision of the above described type of bumper or end sill for mine cars, there are several important features which differ it from conventional mine car end sill construction. It is well known, that under practical conditions of use the end sills of mine cars bow outwardly, due to the heavy load which must be pulled thereby, and the continual jerking which they receive during haulage through the mines. This is true of even the most modern types of mine cars. 15 However, with the improved mine car end sill described, I have found, that under practical conditions of use, the sill is longitudinally reinforced to effectively withstand transverse bending, by reason of the transverse parallel connection of the walls or plates 27, 41, and 46. As another improved feature, in conventional mine car end sills or bumpers, there is a space provided on the end sill between upper and lower flanges for receiving the chain links of the coupling chain. 20 Very often the upper flange becomes bent out of position, and destroys the efficiency of the entire end sill. Furthermore, there are many times when it is dangerous for a person to couple mine cars together, as the operator's hand is liable to become crushed between the ordinary top plate and the filler piece, either directly, or by reason of the links squeezing the operator's hand. In other words, the links do not have sufficient clearance in conventional construction, but in the improved form of invention herein set forth, the links occupy an unobstructed relation laterally of the draw bar body and have no overhanging flanges which might become bent or the cause of crushing an operator's hands or fingers. Furthermore, the chain is kept in an out of the way position at all times and cannot become damaged.

50 In the modified form of end sill or bumper construction shown in Figures 11 to 14 inclusive, there are many details similar to the preferred form of invention, and insofar as applicable, similar reference characters apply to corresponding parts both in the preferred and modified forms of invention. However, in the modified form of invention, which may be appropriately designated by letter F, the supporting member 26^a is not provided with a top attaching flange, but the plate portion 27^a thereof forming the transverse wall between the side sill, is provided with a notch or recess 28^a inwardly from the top edge 29^a thereof, which receives the draw bar body 68^a at its juncture with the rear attaching leg or flange 60, as shown in Figure 11. The mine car floor or bottom D' is extended toward the end and flanged downwardly at 20^a, shown in Figure 11, and riveted over the outer surface of the reinforcing plate portion 47^a of the angle clip 46 by the bolts 56^a, which correspond to the bolts 56 above described, for the preferred embodiment of this invention. It is also to be noted, from Figures 13 and 14, that the reinforcing plates or walls 47^a and 41^a, which correspond to the walls 47 and 41 of the members 46 and 40 of the preferred form of invention respectively, are notched inwardly of the top edges thereof at 48^a

and 48^b respectively, to accommodate the longitudinally extending draw bar body 68^a in the position shown in Figure 11. Otherwise, the details of the modified form of invention are the same as above described for the preferred form of invention.

80 Various changes in the shape, size, and arrangement of parts may be made to the forms of invention herein shown and described, without departing from the spirit of the invention or the scope of the claims.

85 I claim:

1. In a mine car bumper and end sill construction the combination with a mine car frame including side beams, of an end supporting wall secured at its ends to the ends of the side beams, upper and lower angle members each including an upright flange and a horizontal flange, the upright flanges of said angle members being overlapped one upon the other and both overlapping upon the end wall and all secured together in a rigid reinforcing riveted relation with the horizontal flanges thereof relatively spaced, and a cushioning filler piece between said horizontal flanges of the angle members and extending beyond the outer edges of said horizontal flanges.

90 2. In a mine car end sill structure the combination of a frame including side beams, a rear upright metal wall having side flanges secured at the ends of the side beams, a rigid integral substantially horizontal attaching flange at the top of the end wall extending away from the car frame, bumper means on the opposite side of the rear wall from the car frame, a substantially L-shaped coupling bar including a leg rigidly attached along its length to the frame facing side of the rear wall and a horizontal narrow bar disposed above the attaching flange of the rear wall and extending from the mine car frame and being secured to the attaching flange intermediate its ends, and a releasable coupling connected with the draw bar and the bumper means.

95 3. In a railway car the combination with side sills, of a plate metal bottom extended outwardly in the direction of the length of the car beyond the rear ends of the side sills, an upright end wall secured to the ends of the side sills having a top horizontal flange rigidly secured in abutment beneath and to the said extended portion of the plate metal bottom, a separate draw bar member secured to the upright wall and extending outwardly in the direction of the length of the mine car, and a bumper construction secured to the upright wall in spaced relation below said bar, the bumper construction and bar having apertures to receive a coupling bolt.

100 4. In an end sill construction for mine cars a rear upright wall having end attaching portions to be connected to the side beams of a car frame, an angle member of substantially the same length as the upright end wall including an upright wall plate portion abutted against the outer surface of the end wall and secured along its entire length therewith and including a lower horizontal flange extending transverse to the end wall, a second elongated angle member of substantially the same length as said end wall and including an upright wall plate overlying and secured along its entire length to both the upright wall plate of the first mentioned angle member and said end wall, said second angle member also including a horizontal flange disposed in spaced relation above the horizontal flange of the first angle member, a cushioning device associated with said horizontal flanges and engaged against the upright wall

of the first mentioned angle member and at its outer portion projecting beyond the outer edges of the said horizontal flanges.

5. In a mine car bumper and end sill construction the combination with a mine car frame including side beams of an end supporting wall secured at its ends to the ends of the side beams, upper and lower angle members each including an upright flange and a horizontal flange, one of the angle members having a higher upright flange than the other angle member, the upright flanges of said angle members being secured in overlapping abutting relation with each other with the angle member having the higher upright flange abutting against the rear face of the rear wall and with the horizontal flanges of the angle members in relatively spaced relation, said rear wall and upright flanges of the angle members being riveted together and the upright flanges and rear wall being all of substantially the same length, and a cushioning bumper piece associated with the horizontal flanges of the angle members.

6. In a mine car the combination of an end sill having a releasable coupling member, a chain connected with the releasable coupling member, a latch-like lever pivoted upon the end sill having an end adapted to be moved for releasably supporting said end of the chain to hold the chain inoperative upon the end sill, said end sill including a bumper construction below the chain when the latter is inoperatively supported.

7. In a mine car bumper and end sill construction the combination with a mine car frame including side beams, an upright end wall secured at its ends to the ends of the side beams, a pair of angle members each including an upright flange and a horizontally disposed flange, one of said angle members having an upright flange which is appreciably higher than the upright flange of the other angle member, the upright flanges of said angle members each being of substantially the same length as the end wall and being rigidly secured substantially throughout their entire lengths to each other and to the said end wall, with the higher upright flange abutting against the rear surface of the rear wall and the shorter upright flange abutting against the rear surface of the higher upright flange, the top edges of said upright flanges of said angle members lying substantially flush so that the horizontal flanges thereof are disposed in relatively spaced relation at the lower ends of said upright flanges, and a cushioning bumper member associated with the horizontal flanges of the angle members.

8. In an end sill construction for mine cars, a rear upright wall having end attaching portions to be connected to the side beams of a car frame, an angle member of substantially the same length as the upright end wall including an upright wall flange abutted throughout its height and length against the rear surface of the end wall and rigidly secured throughout its height and length therewith, said angle member having a lower horizontal flange extending transverse rearwardly therefrom, a second elongated angle member of substantially the same length as said end wall including an upright flange of less height than the upright flange of the first mentioned angle member and positioned upon the rear sur-

face of the upright flange of the first mentioned angle member and secured thereto and to the end wall throughout the length and height thereof, said upright flange of the second mentioned angle member being secured to the upper portion of the upright flange of the first mentioned angle member, the second mentioned angle member having a lower horizontal flange located in spaced relation above the lower horizontal flange of the first mentioned angle member, a cushioning device associated with said horizontal flanges, and a narrow horizontal draw bar body rigidly secured for transmittal of strains to the rear upright wall and extending rearwardly horizontally in spaced relation above the horizontal flange of the second mentioned angle member at a point about midway between the ends of said horizontal flange last mentioned, and a coupling pin associated with said draw bar body and horizontal flanges of the angle members.

9. In a mine car bumper and end sill construction, the combination with side beams, of an end supporting wall carried by said beams, an upper angle member and a lower angle member, each of said angle members including an upright flange and a horizontal flange, the upright flanges of the upper and lower angle members extending upwardly from their horizontal flanges, secured together in overlapped relation one upon the other and to said end supporting wall, with their upper margins in the same horizontal plane and with their horizontal flanges in spaced relation, and a cushioning filler piece between said horizontal flanges.

10. In a mine car bumper and end sill construction, the combination with side beams, of an end supporting wall, carried by said beams, provided with an outwardly directed flange at its upper portion, an upper angle member and a lower angle member, each of said angle members including an upright flange and a horizontal flange, the upright flanges of the upper and lower angle members extending upwardly from their horizontal flanges, secured together in overlapping relation one upon the other and to said supporting wall with their upper marginal portions engaging the under-side of said outwardly directed flange of said end supporting wall, and with their horizontal flanges in spaced relation, and a cushioning filler piece between said horizontal flanges.

11. In a mine car bumper and end sill construction, the combination with side beams, of an end supporting wall carried by said beams, provided with a notch at its upper marginal portion intermediate the ends of the wall, an upper angle member and a lower angle member, each of said angle members including an upright flange and a horizontal flange, the upright flanges of the upper and lower angle members extending upwardly from their horizontal flanges, secured together in overlapping relation one upon the other and to said supporting wall and provided at their upper marginal portions with notches aligning with the said notch of said end supporting wall, the horizontal flanges of the upper and lower angle members being in spaced relation, a cushioning filler piece between said horizontal flanges, and a draw bar body extending into the notches of said end supporting wall and upright flanges of said upper and lower angle members.

ARMISTEAD R. LONG.
